[57] **CLAIM**

The ornamental design for a combined vision tester and recharging stand therefor, as shown and described.

DESCRIPTION

FIG. 1 is a perspective view of the combined vision tester and stand therefor assembled together;

FIG. 2 is a top plan view of the vision tester;

FIG. 3 is a rear elevational view of the vision tester;

FIG. 4 is a front elevational view of the vision tester;

FIG. 5 is a right side, elevational view, the left side being substantially a mirror image thereof; and

FIG. 6 is a bottom plan view of the vision tester;

FIG. 7 is a top plan view of the recharging stand;

FIG. 8 is a rear elevational view of the recharging stand;

FIG. 9 is a front elevational view of the recharging stand;

FIG. 10 is a right side, elevational view, the left side being substantially a mirror image of the recharging stand;

FIG. 11 is a bottom plan view of the recharging stand; and,

FIG. 12 is a front elevational view of the combined vision tester and recharging stand.
